UNITED STATES PATENT OFFICE.

HUGH YOUNG EVERETT, OF RENOUS BRIDGE, NEW BRUNSWICK, CANADA, ASSIGNOR TO MARTHA A. EVERETT, OF RENOUS BRIDGE, CANADA.

TOOL-GUIDING DEVICE.

No. 884,374.

Specification of Letters Patent.

Patented April 14, 1908.

Application filed May 25, 1907. Serial No. 375,636.

To all whom it may concern:

Be it known that I, HUGH YOUNG EVERETT, a citizen of the United States of America, residing at Renous Bridge, county of Northumberland, in the Province of New Brunswick, Canada, have invented certain new and useful Improvements in Tool-Guiding Devices; and I do hereby declare that the following is a full, clear, and exact description 10 of the invention, such as will enable others skilled in the art to which it appertains to make and use the same.

My invention relates to tool guides.

The object of my invention is to provide 15 an easily removable guide for the shank of a pneumatically or similarly operated tool.

A further object is to provide means for supporting the lower end of a barrel of a pneumatic actuating device for operating the 20 tool.

My invention consists of the construction, combination and arrangement of parts, as herein illustrated, described and claimed.

Ordinarily, these tools are fitted into the 25 mouth of the barrel of the pneumatic actuating member, and when the lower end of the barrel becomes worn, the efficiency of the tool becomes impaired. It is to provide a guide for the tool to prevent wear on the 30 lower end of the barrel, and to thus avoid this difficulty, that my invention is designed. It is also designed to provide means for the insertion of tools of different sizes by using plates having openings therein of different 35 sizes.

In the accompanying drawings, forming part of this application, I have illustrated one form of embodiment of my invention, in which drawings similar reference characters 40 designate corresponding parts, and in which:

Figure 1 is a side elevation showing the application of my invention to the lower end of the barrel of a pneumatic actuating device; Fig. 2 is a transverse horizontal section taken 45 approximately on line 2—2 of Fig. 1, looking in the direction indicated by the arrow; Fig. 3 is an end elevation showing the application of my invention to the lower portion of the barrel of a pneumatic actuating member; Fig. 4 is a longitudinal vertical section taken 50 approximately on line 4—4 of Fig. 2, looking in the direction indicated by the arrow; and, Fig. 5 is a vertical transverse section taken approximately on line 5—5 of Fig. 2.

Referring to the drawings, 1 designates a

lower supporting plate, provided with guide slots 2 in its edges. Where the tool is used with means for adjusting the same vertically, these slots are adapted to receive suitable guides.

The lower end of the barrel 3 of the pneumatic actuating mechanism is provided with a shoulder 4 and a reduced portion 5, adapted to contact respectively with the shoulder 6 on the plate 1 and to pass through the opening 7 in said plate. For the purpose of securing the pneumatic tool, bolts 8 are disposed through the plate 1, and are adapted to be connected to a suitable support, such as a similar plate 1 at the upper end of the barrel 3. On its under face the plate 1 is provided with parallel longitudinal depending flanges 9, having on their lower edges the inwardly extending lugs 10.

Disposed on the lugs 10 is a guide plate 11, 75 provided with an opening 12 of less dimension than the opening 7 in the plate 1, so that it is impossible for the shank A of the tool to bear against the mouth or lower end of the barrel 3, in the ordinary operation of the tool. 80 The opening 12 is preferably square because the shank A is generally square, and it is desired to prevent rotation thereof. When a round shank A is used, the squared opening in no way prevents the rotation thereof, but 85 presents four wearing points only, which is an advantage in the practical operation of the tool.

The flanges 9 are connected intermediate of their ends by the integral webs 13, which 90 are also integral with the plate 1 and project downward to a point above the lugs 10, so as to leave a space between the upper surface of the lugs 10 and the lower surface of the webs, equal to the thickness of the plate 11. 95

After the plate 11 is placed in position on the lugs 10, the bolts 14 are disposed transversely through the flanges 9 and nuts 15 placed thereon. This construction permits the ready removal of the plate 11 for the purposes of repair and removal.

Having thus fully described my invention, what I claim as new, and desire to secure by Letters Patent, is:—

1. A tool guide comprising a supporting plate having an opening therein and having guide slots in its edge, means for securing the plate, and a tool guiding plate provided with an opening therein of less dimension than the opening in the supporting plate and disposed 110

in alinement therewith and means for securing said tool guiding plate.

2. A tool guide comprising a supporting plate having an opening therein and a projecting shoulder, means for securing the plate and a removable tool guiding plate carried by the supporting plate.

3. A tool guide comprising a plate having an opening and provided with depending flanges, a tool guiding plate disposed between the flanges and provided with an opening, and means for removably securing the tool guiding plate.

4. A tool guide comprising a supporting plate having an opening and provided with depending flanges having inwardly extending lugs, a tool guiding plate disposed between the flanges on the lugs and provided with an opening, and means for removably securing the tool guiding plate between the flanges.

5. A tool guide comprising a supporting plate having an opening therein and provided with depending flanges connected by integral webs and provided with inwardly extended lugs, a tool guiding plate disposed between the flanges on the lugs and beneath the webs and provided with an opening, and

means for removably securing the guiding plate between the lugs and the webs.

30

6. A tool guide comprising a plate having an opening therein and provided with depending flanges having inwardly extending lugs, a removable plate provided with an opening and disposed on the lugs, and securing members at each end of the removable plate.

7. A tool guide comprising a plate having an opening therein and provided with depending flanges having inwardly extended lugs, a removable plate provided with an opening disposed on the lugs, bolts disposed transversely through the flanges at each end of the removable plate, and nuts on the bolts.

8. A tool guide comprising a supporting plate with a central opening therein, and a tool guiding plate secured under the supporting plate and provided with an opening in alinement with and of less dimension than the opening in the supporting plate.

In witness whereof I have hereunto set my hand in the presence of two witnesses.

HUGH YOUNG EVERETT.
